(57) **CLAIM**

We claim the ornamental design for the combined insect trap and bait station holder, as shown and described.

DESCRIPTION

FIG. 1 shows a front, top, and left side perspective view of an combined insect trap and bait station holder in accordance with the present invention;

FIG. 2 shows a front, bottom, and left side perspective view of the combined insect trap and bait station holder of FIG. 1;

FIG. 3 shows a front elevational view of the combined insect trap and bait station holder of FIG. 1;

FIG. 4 shows rear elevational view of the combined insect trap and bait station holder of FIG. 1;

FIG. 5 shows a left side elevational view of the combined insect trap and bait station holder of FIG. 1, wherein the right side elevational view and the left side elevational view of the insect trap or insect bait station of FIG. 1, are identical;

FIG. 6 shows a top elevational view of the combined insect trap and bait station holder of FIG. 1;

FIG. 7 shows a bottom elevational view of the combined insect trap and bait station holder of FIG. 1;

FIG. 8 shows the front, top, and left side perspective view of the insect or insect bait station trap holder of FIG. 1, along with a line 9 and line 10 along which sectional views of FIG. 8 are taken;

FIG. 9 shows a sectional view of the combined insect trap and bait station holder of FIG. 1, taken along the line 9 shown in FIG. 8;

FIG. 10 shows a section view of the combined insect trap and bait station holder of FIG. 1, taken along the line 10 shown in FIG. 8;

FIG. 11 shows the front, top, and left side perspective view of the insect or insect bait station trap holder of shown in FIG. 1 but with a known insect trap or insect bait station shown in broken lines inside of the combined insect trap and bait station holder, wherein the insect trap or insect bait station shown in broken lines forms no part of the claimed design; and,

FIG. 12 shows the front elevational view of the combined insect trap and bait station holder of FIG. 3, but with a known insect trap or insect bait station shown in broken lines inside of the combined insect trap and bait station holder,

(Continued)

wherein the insect trap or insect bait station shown in broken lines forms no part of the claimed design.
